BELT AND CHAIN HANGER

Grayce T. Stetson, Providence, R.I., assignor to Jewels by April, Inc., Providence, R.I., a corporation of Rhode Island

Filed May 26, 1969, Ser. No. 17,336

Term of patent 14 years

Int. Cl. D6—07

U.S. Cl. D80—8

FIG. 1

FIG. 2

FIG. 3

FIG. 4

FIG. 5

FIG. 6

FIG. 1 is a front elevational view of a belt and chain hanger showing my new design;

FIG. 2 is a rear elevational view thereof;

FIG. 3 is a top plan view thereof;

FIG. 4 is a bottom plan view thereof;

FIG. 5 is an end elevational view looking from the left with respect to FIG. 1; and

FIG. 6 is an end elevational view looking from the right with respect to FIG. 1.

I claim:

The ornamental design for a belt and chain hanger, substantially as shown.
